(57) **CLAIM**

The ornamental design for a pet feeding cabinet as shown and described.

DESCRIPTION

FIG. 1 is a front, right and top perspective view of a first embodiment of a pet feeding cabinet, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the pet feeding cabinet of FIG. 1 showing the drawer open.

FIG. 10 is a front, right and top perspective view of a second embodiment of the pet feeding cabinet.

FIG. 11 is a rear, left and bottom perspective view of FIG. 10.

FIG. 12 is a front elevation view of FIG. 10.

FIG. 13 is a rear elevation view of FIG. 10.

FIG. 14 is a left side elevation view of FIG. 10.

FIG. 15 is a right side elevation view of FIG. 10.

FIG. 16 is a top plan view of FIG. 10.

FIG. 17 is a bottom plan view of FIG. 10; and,

FIG. 18 is another front, right and top perspective view of the pet feeding cabinet of FIG. 10 showing the drawer open. The dashed broken lines depict portions of the pet feeding cabinet that form no part of the claimed design.

1 Claim, 18 Drawing Sheets
